UNITED STATES PATENT OFFICE.

HOWARD A. CARSON, OF BOSTON, MASSACHUSETTS.

APPARATUS FOR MOVING EARTH.

SPECIFICATION forming part of Letters Patent No. 228,980, dated June 22, 1880.

Application filed February 27, 1880.

To all whom it may concern:

Be it known that I, HOWARD ADAMS CARSON, a citizen of the United States, residing at Boston, in the county of Suffolk and State of Massachusetts, have invented a new and useful System and Apparatus for Hoisting and Moving Earth in Trenches; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

By this system four or any other number of tubs and contents are hoisted in the trench, then moved horizontally over and lengthwise of said trench as far as desirable, and there dumped. The tubs are then returned and lowered to the points from which they were originally hoisted, and the process repeated by substituting tubs which have been filled while the others were gone.

The apparatus is so arranged that the same power which hoists the tubs also moves them backward and forward to and from the dumping-place without disconnecting the tubs from the ropes which hoisted them. The source of power for this hoisting and moving horizontally will usually be an engine with winding-drums; but, where desirable, other sources, such as horses, &c., may be employed.

The figure marked 50, Sheet 1, is an elevation of about one-half of one of the tubs used in this apparatus. The half of the tub not shown is exactly like that shown.

The trunnions, of which *a* is one, are placed so as to be below the center of gravity of the loaded tub, which will thus readily turn and discharge its load, if not kept upright by a suitable device.

To the bail *b* is welded a hook, *c*, having a straight cylindrical neck. Encircling this neck is the sliding piece *d*. The false bail *e* is rigidly connected with the sliding piece *d* by two metal straps, of which *f* is the front one. The false bail shuts into and can be lifted out of a notched plate, *g*, on each side of the tub. The false bail *e* is forked at *h* about the true bail *b*, so that the latter cannot revolve on the

trunnions *a* when the former is shut into the notched plate *g*.

When the loaded tub is supported by the hook *c* its load can be discharged by lifting the false bail out of the notched plate. This lifting is effected automatically in this system by means of the device shown in section near the sliding piece *d*. Two hinged plates of metal, *i i*, are so placed as to be inclined slightly upward in the direction in which the tubs are compelled to move, one end of the plates being slightly lower and the other end being an inch or so higher than the shelf of the sliding piece *d* when the false bail and plate *g* are in engagement. A top view of the hinged plates *i i* is given in Fig. 58, Sheet 3.

As the tub is moved along horizontally toward the dump it (the tub) passes under the pair of hinged plates *i i*, the slide *d* just above and touching said plates, and by reason of the inclined position of the latter the slide *d* is thus raised, drawing the false bail *e* with it, and the load is discharged. The slide *d* falls to its normal position after passing the plates *i*.

When the tub returns toward the place of hoisting the slide *d* passes under the plates *i*, which, being hinged, readily lift. The bolts *k*, with their nuts, allow the plates *i* to be precisely adjusted as to height.

In the group of figures marked 51 on Sheet 2, *l* is a bolt having an eye at its lower end, through which may be attached the hook *c* of the tub lately described. This eyebolt has a grooved opening near its upper end, that permits the wire rope *m* to be passed through and spliced back to itself, so that the rope *m* may support any weight hung on *l*.

The hatched figure *n* is one of two chambered castings, which are fastened about the eyebolt and spliced by a rivet at *o*. The two chambered castings *n*, when bolted together, are called a cone, though having at its base an inverted hollow frustum.

Fig. 62, Sheet 2, gives a section of the cone and eyebolt (but without the rope *m*) at right angles to the view in group 51. The base of the cone *n* serves as a seat, allowing it to rest on the jaws *p*. In the group at 51, however, the jaws are shown in an open position. They will be further alluded to.

Fig. 52, Sheet 2, is a side, and Fig. 53 an end, elevation of a traveler which forms a prominent part in this apparatus. r is a grooved hoisting-sheave, around part of which passes the hoisting-rope m .

In the side plates, s , are bored holes for the trunnions t of the jaws p . A nearly rectangular hole in the side plates, s , allows the cone n to be seen resting on the jaws p . To these side plates is attached the crank u . By pulling the connecting-bar v to the left the crank u can be partially revolved and its horizontal leg lifted. If, now, the cone n has been previously lifted from the jaws p , the horizontal leg of the crank u will engage successively the pins w of the jaws p , and said jaws will be turned into an open position. The rectangular hole in the side plates allows the jaws p to freely open and close, notwithstanding the projecting pins w .

It will be seen that by pulling the rope m over the sheave r a tub attached to the eye-bolt l might be elevated until the cone n had passed through the jaws p and the latter turned back to their resting-places. The rope m might then be slackened, and the cone n would rest on the jaws p and sustain securely the loaded tub.

A piece of bent iron, 14, is bolted to the tops of the side pieces, s . This bent piece 14 has a hole larger than the diameter of the rope m , but small enough to arrest the upward ascent of the cone n . A section through the middle of the bent piece 14, on a vertical plane perpendicular to the plane of projection of Fig. 52, is given in Fig. 61, Sheet 3.

The traveler is provided with grooved wheels g , which allow it to move on a single rail with its load. The tendency of the traveler to move in the direction of the horizontal pull on the hoisting-rope is resisted by buffers x , which are pulled against stationary counter-buffers on the frame-work which supports the track.

It is to be particularly noticed that if sufficient space is allowed above the wheel r any number of ropes may pass through and connect with the same hoisting-drum or other source of power. This arrangement enables any number of tubs to be simultaneously hoisted, secured to the same number of travelers, and then moved horizontally back and forth by the same engine. Fig. 59, Sheet 3, is a plan section on line 20 21 of Fig. 53, Sheet 2, showing the buffers x of a traveler nearly touching their corresponding counter-buffers 17. The latter, which are not shown on Fig. 53, are rigidly attached to the frame-work which supports the track, and therefore never move except when the whole frame-work is moved.

It is to be remarked that in a train of travelers, such as 52 52 52 52, Fig. 56, Sheet 3, the buffers of the traveler nearest the hoisting-engine and farthest from the place to which the loaded buckets are to be drawn are shortest, and the lengths of the buffers increase on each consecutive traveler. The counter-buffers nearest the hoisting-engine approach nearest to the middle line of the travelers, and in suc-

cession recede therefrom as the lengths of their corresponding buffers increase. This is indicated by the Diagram 60, Sheet 3, where the lengths of the buffers x increase, while the distance of the corresponding counter-buffers from the middle line of the travelers increases from the left to the right of the diagram. This arrangement prevents the buffers of one traveler from engaging with the counter-buffers corresponding with any other traveler when the loaded train is moved to the right or when it is returned empty to the position shown in the diagram.

Fig. 54, Sheet 1, is a side elevation, showing the device used in this apparatus for connecting several sheave-ropes with one drum-rope. The wire ropes terminate in eyes, through which are attached one end of the double hooks y . The other ends of the hooks y are attached to such links of the chains z as shall make the proper adjustment of lengths for seating the cones (such as n , Sheet 2). Each chain is fastened by a bolt between two plates, 1, which are connected by a link, to the swivel and shackle 2. On the drum-rope and near the shackle 2 is firmly spliced a swelling, 3, called a "turk's head." This drum-rope passes through a hole in a timber, 22, which is firmly attached to the frame-work supporting the track. Said hole has a diameter slightly greater than that of the drum-rope, but less than that of the turk's head. The perforated timber in connection with the turk's head thus forms a stop on the drum-rope, and when properly adjusted prevents the latter from being moved too far.

The small traveler 4, having a grooved wheel running on the same track as the large travelers, Figs. 52 and 53, Sheet 2, takes up the sag in the system of ropes.

Fig. 55, Sheet 1, is an end elevation, showing the track 5, on which run the grooved wheels of the travelers before mentioned. It is stiffened by a strip of metal, 6, inside, and by a strip of wood, 7, outside the track, and two strips are continuous and break joints with each other. The two strips also serve as fish-plates at the joints in the track. At such intervals as the ordinary load requires are placed suspending-rods 8, of wood, which are attached to the track and strips by round-headed bolts. The clamps 9 inclose a plank stringer, which latter rests on any suitable truss or trestle-work. Obviously metal might be substituted for wood in members 7, 8, and 9.

Fig. 56, Sheet No. 3, is an elevation, and Fig. 57 a plan, showing one form of this system and apparatus now in use (February, 1880) in excavating for a sewer.

For the sake of clearness, no details are given in Figs. 56 and 57 except such as are necessary to understand the relative disposition of parts and the general method of working. 10 is a division of the trench where excavation is going on. 11 is a division where the sewer is built. The earth excavated in 10 is dumped on the completed sewer at 11. Be-

tween 10 and 11 are one or more divisions of trench (not shown) where the excavation is completed and the processes of building the sewer or preparing its foundation are going on. In 10 it is supposed that the tubs 50 are full and just being hoisted, while the tubs 50₂ in 11 have just been dumped.

Operations are continued as follows: The tubs 50₁ are hoisted by the drum 12 until their cones, such as *n*, Fig. 52, Sheet 2, have passed through their respective jaws, and are then lowered until said cones are seated on said jaws. The drum 12 is now left loose, and the drum 13 is set winding up, so as to pull the train of travelers 52₂ and their attached tubs 50₂ toward the winding-engine. A rope, 15, attached to the traveler 52₂ which is farthest from the engine, is passed around the sheaves 16, and again attached to the rear traveler, 52₁. It thus follows that when the train 52₂, traveling on the near track, is pulled toward the left the train 52₁ on the far track is pulled toward the right. The trains pass each other, and when train 52₂ has arrived in position over 10 it is arrested by the buffers, such as *x*, Figs. 52 and 53, Sheet 2, and the counter-buffers on the frame-work. When the train is stopped the cones lift until arrested by stops, such as 14, Figs. 52 and 53, Sheet 2. An attendant then pulls a bar, such as *v*, Fig. 52, Sheet 2, which connects the crank, such as *u*, Fig. 52, Sheet 2, to the left. This opens the jaws, such as *p*, Sheet 2. The tubs 50₂ are now lowered to the bottom of the trench by unwinding the drum 13, Fig. 57, Sheet 3. The empty tubs 50₂ are now unhooked, and four (not shown) which have been loaded while the former were gone are hooked onto the hoisting-ropes. This process is constantly repeated, first on one side of the trench and then on the other.

In the form of my system and apparatus just described there is provided a rail on each side the trench and a double-drum hoisting-engine. If desirable for any reason, one rail may be employed in place of two, using two sets of tubs in place of four; or two rails can be used and only one drum. In the latter case the tubs on both sides of the trench will be moved simultaneously, and some other power than the engine used for hoisting will be employed in the rearward movement.

It is also obvious that in place of trains of four travelers any other number may be employed.

After the excavation in 10 is completed the whole frame-work, supporting hoisting-engine and all the parts heretofore described, is moved the length of one division-farther from the completed sewer.

The principal advantages of this system and apparatus are—

First, that all operations of excavating and moving the earth are carried on within and

over the trench. This is of especial value in 65 city streets and on steep side hills.

Second, that several tubs can be hoisted simultaneously and moved to the rear simultaneously. Nearly all trenches must be divided by the cross-braces into sections. It is 70 of great convenience, and greatly favors economy, to be able to excavate independently in several sections at once—a result attained by this system.

Third, that the necessary power for hoisting, 75 conveying to the rear, and returning the several tubs is furnished by one engine.

Fourth, that the tubs remain securely attached to the same ropes from the time they leave the bottom until they return, no shifting taking place. This is valuable in securing from danger the men who are working below, and adding to the celerity, therefore economy, of the moving of earth.

Fifth, that the details of this apparatus are 85 simple, easily made, and not likely to get out of order.

Having thus described my invention and shown its usefulness, what I claim as new, and desire to secure by Letters Patent, is— 90

1. An apparatus for hoisting and moving earth in trenches, consisting of a single-track suspension-railway, travelers for hoisting and conveying, adapted thereto, a forward draft-rope branched for each traveler, tubs for holding material, and a rear draft-rope, all combined substantially as shown and described. 95

2. In connection with an apparatus for hoisting and moving earth in trenches, the tub 50, having the hook *c*, the slide *d*, the false 100 bail *e*, and notched plate *g*, also the hinged tripping-plates *i*, combined substantially as described.

3. In connection with an apparatus for hoisting and moving earth in trenches, the 105 hoisting-ropes *m*, having the eyebolt *l*, cone *n*, jaws *p*, adjusting-chains *z*, small traveler 4, turk's head 3, and perforated timber stop 22, combined substantially as described.

4. In connection with an apparatus for 110 hoisting and moving earth in trenches, the traveler 52, having the grooved wheels *q*, the hoisting-sheave *r*, the jaws *p*, the opening-crank *u*, the connecting-bar *v*, the stop 14, and the buffers *x*, combined with the rope *m*, 115 having cone *n*, substantially as described.

5. In connection with an apparatus for hoisting and moving earth in trenches, the suspension-railway 55, having the continuous fish-plates 6 and 7, the suspending-rods 8, and 120 clamps 9, combined substantially as shown and described.

In testimony whereof I have affixed my signature in presence of two witnesses.

HOWARD ADAMS CARSON.
